HEEL ATTACHING MACHINES

Ferman N. Lee, deceased, late of Danvers, Mass., by Dolores R. Lee, executrix, Danvers, and Leonard E. Proulx, Arlington, Mass., assignors to United Shoe Machinery Corporation, Boston, Mass., a corporation of New Jersey

Application April 12, 1957, Serial No. 652,415

5 Claims. (Cl. 1—32)

This invention relates to machines for use in the attachment of heels to shoes and more specifically to improvements for positioning the shoes with relation to the heels in said machines.

In an application for United States Letters Patent Serial No. 655,937, filed April 11, 1957, in the names of Vernon H. Meyer et al., there is disclosed a jack for use in the positioning of shoes, which are mounted on geometrically graded lasts, in a well-known heel loading and attaching machine of the general type disclosed in United States Letters Patent No. 1,157,688, granted October 26, 1915, on an application filed in the name of Lester L. Glidden. The heel loading and attaching machine is called upon to attach heels to shoes which are mounted on arithmetically graded lasts and geometrically graded lasts delivered respectively to the machine in "short runs."

It is an object of the present invention to provide the above loading and attaching machine with means which is adapted quickly and effectively to position in this machine shoes mounted on either of the above types of lasts with a minimum amount of changeover time loss. With the above object in view the illustrative machine is provided with a shoe supporting jack which will accommodate shoes mounted on arithmetically graded lasts and can be quickly modified to accommodate shoes which are mounted on geometrically graded lasts having last positioning plates mounted thereon, said machine also being provided with a pair of back gages which may be selectively moved into active positions for quickly and effectively locating the shoes on arithmetically and geometrically graded lasts respectively mounted on the jack lengthwise in the machine.

The present invention consists in the novel features hereinafter described, reference being had to the accompanying drawings which illustrate one embodiment of the invention selected for purposes of illustration, said invention being fully disclosed in the following description and claims.

In the drawings,

Fig. 1 is an angular view showing a shoe, which is mounted on a geometric last, in the process of having a heel attached to it by the use of the illustrative machine which is of the general type disclosed in said Patent No. 1,157,688 and most of which has been broken away;

Fig. 2 is a side view, partly in section, showing details of the jack and work positioning mechanism of the machine;

Fig. 3 is a view showing in plan the relation of right and left geometrically graded lasts and a heel positioning form at the time that shoes mounted on said lasts are positioned with relation to a heel in said form;

Fig. 4 is a view showing outlines along a heightwise median plane of the heel ends of shoes of four different sizes positioned in the machine ready to be pressed against a heel (not shown) in said form;

Fig. 5 shows, partly in side elevation and partly in section, a shoe, which is mounted on an arithmetically

2

graded last, in the process of having a heel attached to it by the use of the illustrative machine; and

Fig. 6 is an angular view, partly in heightwise median section, of the heel end of a shoe, which is mounted on a geometrically graded last and has had its heel attached by the use of the machine, material which has been trimmed from the periphery of the heel of the shoe subsequent to the heel attaching operation being shown in dash lines.

10 The illustrative machine is described with reference to attaching rubber heels 20 (Figs. 1, 2 and 6) and their base lifts 22, hereinafter referred to as composite heels 24, to the heel seats 26 of outsoles 28 of men's shoes 30 which are mounted on geometrically graded lasts 32 15 having secured to flat upper faces 34 of their back cones 36 positioning plates 38, each of which has flat sides 40 parallel to a center line LCL (Fig. 3) of the last and comprises a flat or planar abutment surface 42 into which extends a thimble 44.

20 The present machine is substantially identical with the machine disclosed in said Patent 1,157,688 and comprises a bracket 46 (Fig. 1) which is secured by nuts 48 to upstanding posts 50 forming part of a main frame 52 (Fig. 2) of the machine. Mounted on the bracket 46 is a carriage 54 which bears on a flat upper surface 56 of the bracket 46 and has at its rear end bores (not shown) for receiving a guide rod 58 secured to the bracket. The carriage 54 is moved against the action of a spring (not shown) to the left, as viewed in Fig. 1, away from its active or attaching position against a stop collar 60, over the upper surface 56 of the bracket 46 in response to movement of a loader block (not shown) from a nail receiving position whereby to "clear" an upper face 62 of a nailing die 64 so that nails 66 (Fig. 6) then in passages (not shown) of the loader block may be dumped from said block into passages 68 of a selected nail "design" in the nailing die, said carriage 54 being moved to its heel attaching position against the stop collar by the spring as the loader block is moved back to its nail receiving position. Mounted for vertical movement in the passages 68 of the nailing die 64 are drivers 70 (Fig. 5) adapted to drive nails, which have been dumped into said passages, into the composite heel 24 and the heel seat of the shoe clamped by mechanism, hereinafter described, against said heel, said nails being clenched against a heel plate 72 of the last.

25 The carriage 54 has an undercut guideway 74 (Fig. 1) for receiving a form or "heel ring" 76 which comprises a bottom plate 78 having passages 80 arranged in predetermined "design" and, when the carriage is in an active or attaching position, is arranged in substantial engagement with the upper surface 62 of the nailing die 64 with its passages in alignment with a plurality of the passages 68 of a predetermined "design" of the nailing die 64, an upper surface of the die being flush with the upper surface 56 of the bracket 46. The form 76 has a cavity 82 adapted fittingly to receive the rubber heel 20 and to locate in a predetermined position in the form, said rubber heel together with the base lift "spotted" to it, the position of the form in the guideway 74 of the carriage 54 being quickly established by the engagement of a spring-pressed plunger 84 which is slidably mounted in a bore (not shown) of the carriage and in a bore (not shown) in said form. The form 76 has secured to it by screws an upper plate 86 having a cavity 88 for receiving and positioning the base lift 22 on the rubber heel 20 in the event that the base lift has not been previously secured or "spotted" to the rubber heel by adhesives or by fastenings. Forms 76 of different sizes and of the same style are so positioned in the carriage 54 that the extreme vertical rear end lines 90 of heel engaging portions thereof are located along a fixed vertical line. The forms 76

may be described as being positioned symmetrically in the machine with the vertical center lines of their rear ends arranged in a fixed vertical heel reference line disposed at right angles to planes respectively of the rims of the attaching faces of the heels positioned in said forms.

The geometrically graded last having the shoe 30 mounted on it is manually presented right side up to a jack 92 (Figs. 1 and 2) swung forward to a predetermined loading and unloading position shown in dashed lines (Fig. 2), the jack then being swung back to a vertical or attaching position shown in full lines (Figs. 1 and 2) with the rear end 94 (Figs. 1 and 4) of a break or feather line 96 of the counter portion of the shoe arranged above and just forwardly of the rear end of an attaching face 98 of the base lift 22 of the composite heel 24 positioned in the form 76.

The main frame 52 of the machine has a vertical guideway 100 (Fig. 2) along which is slidably movable a plunger 102 having formed integral with it a multipart guide housing 104 which has an undercut guideway 106 for receiving a retaining slide 108 having formed integral with it a depending bifurcated boss 110 bored to receive a bearing pin 112. The guide housing 104 and the retaining slide 108 have formed in them overlapping slots (not shown) for receiving a bolt 114 into which is threaded an internally and externally threaded sleeve 116 on which is mounted a handle 118 provided with a pin 120 fitting selectively in one of a plurality of grooves formed in the sleeve. The handle 118 and accordingly the threaded sleeve 116 are turned to bind the retaining slide 108 to the guide housing 104, a nut 122 being provided to secure the threaded sleeve in a clamping position.

The jack 92 comprises a post 124 having at its upper end a narrowed portion fitting between bifurcations of the boss 110 and journaled on the bearing pin 112, said post having mounted on it a spring-pressed toggle plunger 126 having a V-shaped upper end which bears in a notch 128 formed in the bottom of said boss and serves to retain the post in its loading and unloading and its attaching positions.

The lower end of the jack post 124 is bifurcated to receive a T-shaped block 130 (Figs. 1, 2 and 5) the upper end of which has serrations adapted to be interfitted with serrations of a retaining piece 132 fixed to the post and which has arcuate faces adapted to be engaged respectively by arcuate lower faces of the jack post. The block 130 is secured in different angularly adjusted positions on the jack post 124 by a screw 133 which passes through a bore in one bifurcation of the post and an arcuate slot 135 (Fig. 2) in the block and which is threaded into the other bifurcation of the post, the tightening of the screw serving to clamp the block effectively in its adjusted position to the post. A bottom face of the block 130 is flat and has formed in it a transverse dovetail slot 134 which slidably receives a dovetail projection of a guide housing 136, said guide housing being retained against any substantial amount of movement in said slot by a spring-pressed pin 138 (Fig. 2) which fits slidably in a bore of the block and in a recess 140 in the upper face of the housing. The pin 138 may be raised preparatory to moving the housing 136 from the block 130 by lifting a rod 142 secured to the pin along a slot 144 of the block.

The guide housing 136 has formed in it a T-shaped slot or guideway 146 in which slidably fits an abutment slide or slide plate 148. The slide 148 has a slot 150 adapted to receive the lower portion of a stop pin 152 carried by the housing 136 and is constantly urged forwardly by a spring 154 opposite ends of which are attached to the block 130 and to a rod 156 secured to the slide. When the jack 92 is idle a face which forms the rear end of the slot 150 is in engagement with the stop pin 152 (Fig. 2). The abutment slide 148 has secured to it a spindle 158 which projects beyond an abutment

surface 160 of the slide and is adapted to receive the geometrically graded last 32 having a shoe mounted on it, the thimble 44 of said last being slid onto the spindle until the abutment surface 42 of the positioning plate 38 attached to the last engages the abutment surface 160 of the slide. As illustrated in Fig. 3, the central lines LCL of right and left lasts 32 respectively upon which shoes positioned in the machines are mounted, are inclined at equal angles alpha (Fig. 3) to a common vertical median plane 162 of the heel plates 72 of right and left lasts each of which heel plates has an outline defined by its U-shaped edge and is substantially similar to and centralized with respect to the feather line 96 of the counter portion of the shoe mounted on the last. It will be apparent that since shoes are shaped to the last, the vertical median plane 162 of the heel seat of the last is also the vertical median plane of the feather line 96 of the overlasted counter portion of the shoe.

The rear portions of the heel plates 72 of geometrically graded lasts 32 of different sizes and accordingly the rear portions of the feather lines 96 of the overlasted counter portions of shoes 30 of different sizes formed on said lasts, are centered respectively about axes 164 of the thimbles 44 of the lasts. Accordingly, the shoe 30 mounted on the jack may be rotated about the spindle 158 to orient the vertical median plane 162 of the heel plate of the last so that it lies in a vertical median plane 166 of the form 76 and accordingly the composite heel 24 positioned in said form, without shifting the rear end of the shoe lengthwise.

In order that the operator may quickly and effectively orient the shoe 30, mounted on a left or a right geometrically graded last 32 about the spindle 158 into a position in which the vertical median plane 162 of the heel plate 72 of the last shall be coincident with the vertical median plane 166 of the heel form 76 and accordingly of the composite heel 24 positioned in said form as he places the last on the spindle 158, the abutment slide 148 has at its opposite sides vertical slots 168 in which fit respectively a pair of depending stop lugs 170 which are secured by screws 172 to the slide and are engaged respectively by one of the planar side faces 40 of the positioning plate 38 on the last in accordance with whether right or left work is being operated upon.

When the machine is operating upon shoes 30a (Fig. 45) mounted on arithmetically graded lasts 32a which do not have positioning plates mounted on their back cones, a conventional back gage 174 is used to position the shoes lengthwise in the machine. In order to position shoes 30 mounted on geometrically graded lasts 32 lengthwise in the illustrative machine there is provided a back gage 173 which has a flat face 175 adapted to be engaged by the median portion of the back seam line 177 of the shoe and which has secured to it a pin 179 journaled on a bearing flange 181 secured to a shank portion of the conventional back gage 174. The back gage 174 comprises a laterally concave surface 176 which is adapted to be engaged by the rear end of the rand crease 178 of the shoe 30a as the shoe on the abutment slide 148 is moved rearward, against the action of the spring 154, upon the jack 92 which has already been moved to its attaching position determined by the engagement of an upper face 180 of the jack with the bottom of the retaining slide 108. The heightwise elements of the concave surface 176 of the back gage 174 may be described as extending toward of the shoe as they extend toward said rand crease.

The back gage 174 in its lowered gaging position shown in Fig. 5 lies in the path of movement of a loader block (not shown) as it delivers the nails 66 to the passages 68 of the nailing die 64 and accordingly this gage is raised by suitable mechanism, hereinafter described, in response to movement of the jack 92 to its loading and unloading position and is lowered to its operating position as the jack is swung to its attaching position, the loader block

being operated while the jack is in its loading and unloading positions. An upstanding or shank portion of the conventional back gage 174 is provided with guideways 182 for receiving guides 184 of a back gage holder 186 which may be initially moved in directions 188, 190 or lengthwise and widthwise, respectively, of the machine by mechanism such as disclosed in United States Letters Patent No. 1,030,680 granted June 25, 1912, on an application filed in the name of Joseph H. Pope. Secured by a screw 192 to the upper end of the shank portion of the conventional back gage 174 is a chain 194 which meshes with teeth of a sprocket 196 rotatably mounted on the retaining slide 108 and has its upper end attached to a hooked lever 198 which is journaled on the bearing pin 112 and has a face 200 thereof held by the weight of the back gage and its associated parts against an adjusting screw 202 threaded into the jack post 124. The shank portion of the back gage 174 may be referred to as a carrier slide.

Preparatory to attaching composite heels 24a to shoes 30a (Fig. 5) mounted on arithmetically graded lasts 32a which usually do not have positioning plates mounted on them, the depending stop studs 170 are removed from the abutment slide 148, the block 130 being initially secured in a desired angular position on the jack post 124 in accordance with the angle of a top face 34a of the back cone of the arithmetically graded last 32a. Moreover, prior to operating upon regular work the back gage 173 is swung from its active position against the conventional back gage 174, as shown in Figs. 1 and 2, to its inactive or raised position shown in Fig. 5.

When operating upon "regular" work the shoes 30a, mounted on the arithmetically graded last 32a, are presented right side up to the jack 92, a thimble 44a of the last overriding the spindle 158 of the abutment slide 148 of the jack until the top face 34a of the back cone of the last 32a engages the abutment face 160 of the slide. The jack 92 is then swung rearwardly about an axis of the bearing pin 112 until the upper face 180 of the jack engages the retaining slide 108, the operator during this time manually orienting by "eye" the shoe on the spindle in order to aline the median vertical plane 162 of the heel plate 160 and accordingly the feather line 96 of the counter portion of the shoe with the vertical median plane 166 of the composite heel 24a positioned in the form 76, the abutment slide 148 then being moved rearwardly along the T-shaped slot 146 of the guide housing 136 against the action of the spring 154 until the rear end of the rand crease 178 of the shoe engages the lower end of the back gage 174. The screw 202 is initially adjusted to insure that the back gage 174 shall be moved into an operating position in which its lower end receives the rear end of the rand crease of the shoe after the jack 92 has been swung rearward to its attaching position and the shoe on the abutment slide 148 has been moved rearward on the jack against the back gage.

When the shoe 30a has been positioned with relation to the composite heel 24a in the form 76 a clutch (not shown) of the machine is tripped causing the jack 92 to be lowered to press the heel seat 26 of the outsole 28 of the shoe against the attaching face 98 of the heel and then causing the nail drivers 70 to drive the nails 66 into the heel and the heel seat of the shoe, said nails being clenched against the heel plate 72 of the last.

It will be noted, as illustrated in Fig. 4, that when shoes 30 of different sizes built on geometrically graded lasts 32 are positioned in the machine with the flat abutment surfaces 42 of the positioning plates 38 of the lasts 36 in engagement with the abutment surface 160 of the slide 148, said last being oriented on the spindle 158 by the engagement of one or the other of the flat sides 40 of the positioning plate with one or the other of the depending stop lugs 170 secured to the slide 148 and the rear ends 94 of the feather lines 96 of the shoes being vertically arranged above one another, the median por-

tions of the back seam lines 177 of the shoes extend along one another in substantially tangential relation. Accordingly, it will be appreciated that the flat face 175 of the back gage 173, which face extends toewards as it extends upwardly of the shoe, may be effectively engaged by the median portion of the back seam lines 177 of the shoes to position the shoes lengthwise in the machine and vertically above the composite heels 24 positioned in the forms 76 without initial heightwise adjustment of said gage being necessary.

The face 175 of the illustrative back gage 173 is disposed at substantially 7° to a vertical plane extending widthwise of the shoe and passing through said gage, this angle being suitable to accommodate most styles and sizes of shoes. It will be understood that the face 175 of the back gage 173 need not be flat but may be concaved laterally slightly, the transverse radius of curvature of the face of this gage being greater than the transverse radius of curvature of the opposing rear end portion 20 of the shoe positioned in the machine, said concave surface being generated by a line which moves transversely of the shoe and extends toewards of the shoe as it extends upwardly of said shoe. The back gage 173 is so constructed and arranged that its face 175 is arranged as above described when its lower end is in engagement with the surface 176 of the back gage 174. It will be appreciated that various other devices, for example, a screw (not shown) which is adjustably mounted in the shank portion of the back gage 174 may be provided for controlling the active position of the back gage 173.

In view of the foregoing it will be clear that when shoes mounted on the arithmetically graded lasts 32a are being operated upon it is necessary initially to adjust the back gage 174 into predetermined and different heightwise positions every time a shoe of a different size is operated upon whereby to insure that the gage 174 shall be engaged by the rear end of the rand crease 178 of the shoe. The foregoing adjustment consumes considerable time and often the operator fails to make the proper adjustment with the result that the heel is not properly positioned on the shoe. It will also be clear that when "geometric" work only is being operated upon in the illustrative machine it is not necessary initially to adjust the screw 202 as above described to accommodate shoes of different sizes, it having been found that one adjustment of the back gage 173 is sufficient to accommodate most styles and sizes of shoes. For operating exclusively on "geometric" work the back gage 173 may be fixed to the main frame of the machine or to a bracket which forms part of the main frame since that gage in its operating position is located so high above the heel positioning form 76 that it is not engaged by the loader block during the transfer of nails to the nailing die 64.

Preparatory to attaching the composite heels 24 to the shoes 30 which are mounted on geometrically graded lasts 32, the stop lugs 170 are secured by screws 172 to the sides of the abutment slide 148 and the geometric back gage 173 is swung from its raised inactive position shown in Fig. 5 to its active position against the front face 176 of the conventional back gage 174 as shown in Figs. 1 and 2, the flat work engaging face 175 of the gage 173 extending transversely of the shoe and extending toewards of the shoe as it extends upwardly of the shoe.

In operating upon the shoe 30 mounted upon the geometrically graded last 32 the operator presents the last to the jack 92, the thimble 44 of said last being received by the spindle 158 of the abutment slide 148 until the flat upper surface 42 of the positioning plate 38 of the last engages the abutment surface 160 of the slide, the operator swinging the shoe and accordingly the last on the spindle until one or the other of said flat sides 40 of the positioning plate engages one of the stop lugs 170 (depending upon whether a right or left shoe is being operated upon) to position the vertical median plane 162 of the heel plate 160 of the last and accordingly the heel

seat of the shoe on the last in coincident relation with the vertical median plane 166 of the form 76 and the composite heel 24 positioned in said form. The jack 92 during this time may be swung rearwardly until its face 180 engages the bottom of the retaining slide 108, the work then being moved rearwardly on the jack post together with the abutment slide until the median portion of the back seam line 177 of the shoe engages the face 175 of the back gage 173 thereby correctly positioning the shoe lengthwise in the machine. The clutch (not shown) of the machine is then tripped with the result that the plunger 102 is lowered by power causing the heel seat 26 of the outsole 28 of the shoe 30 to be forced against the attaching face 98 of the composite heel 24, the nails 66 thereafter being driven into the heel and the heel seat 15 of the shoe to attach the heel to the shoe.

The planar face 175 of the back gage 173 may be described as being disposed at right angles to a vertical median plane of the heel positioned in the form and as forming with a plane of the rim of the attaching face of the heel a dihedral angle of about 83° which includes the heel end of the shoe. The planar face 175 may also be defined as extending forwardly of the shoe 30 as it extends upwardly of said shoe and as being disposed at a slight angle to a vertical plane extending transversely of the T-shaped slot or guideway 146.

The face 175 of the back gage 174 may be described as being adapted to position shoes of different sizes as lengthwise in the machine with the rear ends 94 of their feather lines 96 arranged in a vertical shoe reference line substantially parallel to or substantially coinciding with a heel reference line of the extreme vertical rear end line 90 of the cavity 82.

Having thus described our invention, what we claim as new and desire to secure by Letters Patent of the United States is:

1. In a heel attaching machine employing forms for supporting and positioning heels of different sizes, means for symmetrically positioning any one of said forms selectively widthwise in the machine with a vertical central line of its heel engaging portion arranged in a fixed vertical heel reference line, a jack for supporting a shoe on a geometrically graded last, said jack being movable between a loading and unloading station and an attaching station, and a back gage which is movable vertically with relation to said form in response to movement of the jack and has a fixed vertical operating position with relation to the jack at said attaching station and which has a face engaged by the median portion only of the back seam line of the shoe on the jack moved to the attaching station for positioning shoes of different sizes lengthwise in the machine with the rear ends of their feather lines arranged in a shoe reference line substantially coincident with said heel reference line, said face of the back gage being formed by the generation of a line which extends generally heightwise of the shoe and is moved parallel to itself transversely of the shoe and which diverges at a slight angle from said heel reference line as it approaches the heel supporting and positioning form in the machine.

2. In a heel attaching machine, a form for supporting a heel having an attaching face a rim of which lies substantially in a horizontal plane, a jack comprising a post and a plate slidably mounted on the post and adapted to receive a geometrically graded last upon which is mounted a shoe to which the heel is to be attached, means movable with the plate for orienting the shoe upon the plate whereby to align a vertical median plane of the heel end of the shoe with a vertical median plane of the rim of the heel, a power operated plunger, said jack being mounted for pivotal movement on the plunger between a loading and unloading position and a heel attaching position, and a back gage which is vertically movable to a fixed operating position in response to movement of the jack to its heel attaching

5 position and which has a face adapted to be engaged by the median portion only of the back seam line of the shoe whereby to position the oriented shoe lengthwise on the jack irrespective of its size, said face at and adjacent to its portion of contact with the back seam line of the shoe being formed by vertical elements forming an acute angle with the plane of the rim of the attaching face of the heel in the form.

3. In a heel attaching machine, a nailing die, a form for positioning a heel with relation to said die with a rim of the attaching face of the heel arranged substantially in a plane, a jack for supporting shoes mounted or arithmetically and geometrically graded lasts heightwise and widthwise with relation to the form, a first back gage engaged by the rear end of the rand crease of one of the shoes mounted on one of the arithmetically graded lasts on the support whereby to position the shoe lengthwise with relation to the form, and a second back gage which is movable between active and inactive positions on said first back gage and when in its active position is engaged by the median portion only of the back seam line of one of the shoes mounted on one of said geometrically graded lasts on the support whereby to position the shoe lengthwise with relation to said form, said second back gage having a planar face which is disposed at right angles to the vertical median plane of the heel in said form and which lies in a plane, forming with a plane of the rim of the attaching face of the heel in said form, a dihedral angle which is approximately 83° and includes the rear end of the shoe.

4. In a heel attaching machine, a nailing die, a form for supporting and positioning a heel with relation to said die, a back gage, a jack cooperative with said back gage in the positioning of a shoe mounted on a geometrically graded last having a back cone provided with a positioning plate which has an abutment surface and a thimble extending into said surface and opposite sides of which are symmetrically arranged with relation to a center line of the last, said jack comprising a post which is mounted for pivotal movement between a loading and unloading position and an attaching position and which has a rectilinear guideway, an abutment slide which is slidably mounted in the guideway, said abutment slide having an abutment surface, a spindle projecting beyond said surface, and a pair of laterally spaced orienting studs, said spindle being adapted fittingly to receive the thimble and to allow the abutment surface of the positioning plate of the last to engage the abutment surface of the abutment slide and one of said studs being engaged by one of the sides of said positioning plate of the last in accordance with whether a right or left shoe is being operated upon, whereby to position the vertical median plane of the heel seat of the shoe in a vertical median plane of the heel in said form, and a back gage having a substantially planar face which is engaged by the median portion only of the back seam line of the shoe and which extends upwardly and forwardly of the shoe at a slight angle to a plane disposed transversely of and at right angles to said guideway.

5. In a machine for attaching heels to shoes mounted on arithmetically and geometrically graded lasts having planar back cone top faces respectively, into which thimbles extend, and back cone side faces, a nailing die, a form for supporting and positioning a heel with relation to said die, a jack post movable between a loading and unloading and an attaching position, a carrier slide movable in response to movement of the jack post, a slide plate which is movable on said post in a rectilinear path toward and away from the carrier slide and has an abutment face and which has mounted on it a spindle and studs projecting beyond said abutment face, said spindle being adapted successively to receive thimbles of arithmetically and geometrically graded lasts until the back cone top faces of said lasts engage said abutment

face of said slide plate and one of said studs being adapted to be engaged respectively, in accordance with whether a right or left shoe is being operated upon, by one of the back cone side faces of geometrically graded lasts to orient the heel ends of shoes on the spindle with their vertical median planes lying in a vertical median plane of the heel in the heel form, means mounting said studs for removal from the side plate to enable shoes on arithmetically graded lasts to be oriented manually to their proper positions on the spindle by the operator, a first back gage which is mounted on the carrier slide and is adapted to be engaged by the rear ends of the rand creases of shoes which are mounted on said arithmetically graded lasts and are oriented on the slide plate whereby to position the shoes lengthwise, and a second back gage which is pivotally mounted between active and inactive positions on the carrier slide and has a planar face adapted to be engaged by the median portions only

10

5 of back seam lines of the shoes mounted on geometrically graded lasts and oriented on the slide plate whereby to position said shoes lengthwise, said planar face of said second back gage in its active position being disposed at right angles to the vertical median plane of the heel positioned in the form and forming with a plane of the line of the attaching face of said heel a dihedral angle of approximately 83° which includes the heel end of the shoe.
